US0D1099943S

(12) **United States Design Patent** (10) Patent No.: US D1,099,943 S
Heiner et al. (45) Date of Patent: ** Oct. 28, 2025

(54) **DISPLAY PANEL OR PORTION THEREOF WITH A TRANSITIONAL MIXED REALITY GRAPHICAL USER INTERFACE**

(71) Applicant: **MAGIC LEAP, INC.**, Plantation, FL
(US)

(72) Inventors: **Cole Parker Heiner**, Fort Lauderdale, FL (US); **Lorena Pazmino**, Wilton Manors, FL (US); **Gregory Minh Tran**, Miami, FL (US); **Paul Armistead Hoover**, Plantation, FL (US)

(73) Assignee: **Magic Leap, Inc.**, Plantation, FL (US)

(**) Term: **15 Years**

(21) Appl. No.: 29/948,708

(22) Filed: Jun. 21, 2024

(57) CLAIM

The ornamental design for a display panel or portion thereof with a transitional mixed reality graphical user interface, as shown and described.

DESCRIPTION

FIG. 1 is a front view of a display panel or portion thereof with the graphical user interface showing a first image in a sequence of a first design;

FIG. 2 is a front view of a display panel or portion thereof with the graphical user interface showing a second image in the sequence of the first design;

FIG. 3 is a front view of a display panel or portion thereof with the graphical user interface showing a third image in the sequence of the first design;

FIG. 4 is a front view of a display panel or portion thereof with the graphical user interface showing a first image in a sequence of a second design;

FIG. 5 is a front view of a display panel or portion thereof with the graphical user interface showing a second image in the sequence of the second design;

FIG. 6 is a front view of a display panel or portion thereof with the graphical user interface showing a third image in the sequence of the second design;

FIG. 7 is a front view of a display panel or portion thereof with the graphical user interface showing a first image in a sequence of a third design;

FIG. 8 is a front view of a display panel or portion thereof with the graphical user interface showing a second image in the sequence of the third design;

FIG. 9 is a front view of a display panel or portion thereof with the graphical user interface showing a third image in the sequence of the third design;

FIG. 10 is a front view of a display panel or portion thereof with the graphical user interface showing a first image in a sequence of a fourth design;

FIG. 11 is a front view of a display panel or portion thereof with the graphical user interface showing a second image in the sequence of the fourth design;

FIG. 12 is a front view of a display panel or portion thereof with the graphical user interface showing a third image in the sequence of the fourth design;

FIG. 13 is a front view of a display panel or portion thereof with the graphical user interface showing a first image in a sequence of a fifth design;

FIG. 14 is a front view of a display panel or portion thereof with the graphical user interface showing a second image in the sequence of the fifth design;

FIG. 15 is a front view of a display panel or portion thereof with the graphical user interface showing a third image in the sequence of the fifth design;

FIG. 16 is a front view of a display panel or portion thereof with the graphical user interface showing a first image in a sequence of an sixth design;

FIG. 17 is a front view of a display panel or portion thereof with the graphical user interface showing a second image in the sequence of the sixth design;

FIG. 18 is a front view of a display panel or portion thereof with the graphical user interface showing a third image in the sequence of the sixth design;

FIG. 19 is a front view of a display panel or portion thereof with the graphical user interface showing a first image in a sequence of a seventh design;

FIG. 20 is a front view of a display panel or portion thereof with the graphical user interface showing a second image in the sequence of the seventh design; and,

FIG. 21 is a front view of a display panel or portion thereof with the graphical user interface showing a third image in the sequence of the seventh design.

The appearance of the image sequentially transitions between the images shown in each of FIGS. 1 through 3, FIGS. 4 through 6, FIGS. 7 through 9, FIGS. 10 through 12, FIGS. 13 through 15, FIGS. 16 through 19, and FIGS. 20 through 21. The process or period in which one image transitions to another forms no part of the claimed designs. The outermost broken line rectangle illustrates a display panel or portion thereof that forms no part of the claimed designs. The remaining broken lines illustrate portions of a graphical user interface or a mixed reality environment, and form no part of the claimed designs.
